UNITED STATES PATENT OFFICE.

STANLEY VENGRIN AND JOHN M. JOHNSON, OF DULUTH, MINNESOTA.

GRINDER.

Application filed April 7, 1922. Serial No. 550,263.

To all whom it may concern:

Be it known that we, STANLEY VENGRIN and JOHN M. JOHNSON, each a citizen of the United States, residing at Duluth, in the county of St. Louis and State of Minnesota, have invented certain new and useful Improvements in Grinders, of which the following is a specification, reference being had therein to the accompanying drawing.

10 This invention relates to grinders for hollow chisels.

The object of the invention is to obviate the necessity of sharpening such chisels by hand which is frequently practiced at the 15 present time and to accomplish a more desirable job of sharpening.

Other objects and advantages will appear in the further description of the invention.

Referring to the accompanying drawing 20 in which like reference characters indicate like parts,

Figure 1 is a sectional view with portions in elevation of one of the grinders having a hollow chisel applied thereto,

25 Figure 2 is an elevation of one of the hollow chisels; and

Figure 3 is an end view of the cutting end of the chisel.

The grinder comprises a cylindrically 30 shaped body portion 1 having a conically shaped outer end 2, the body portion 1 being embedded as by babbitt or the like, illustrated at 3, within a tapered holding chuck or head 4, the babbitt having an axial bore 35 therein which is internally screw threaded as at 5, by which it may be mounted upon a rotative spindle or shaft 6 actuated in any desired manner.

7 represents a hollow mortising tool com- 40 monly used in wood working machinery the

exterior of the cutting bit of the tool being square in cross section and having a round axial bore therethrough. In sharpening the cutting end of this tool upon the grinder the tool is held in axial alignment with the 45 grinder and crowded against same until the end of the tool is completely countersunk by the action of the grinder which will form concaved arcuately shaped cutting edges on the four sides of the tool, as illustrated at 8. 50

If it is desired to lessen the depth of the concaved portion and yet perfectly sharpen each corner of the tool, a tipping of the tool out of axial alignment with the grinder will accomplish the desired result, as is obvious, such positioning of the tool being illustrated in dotted lines at 9 in Figure 1, and it is apparent that a more blunt conically shaped grinder would countersink the tool less, or a sharper one than that shown would countersink the tool more, so that any desired edge on the tool may be readily accomplished. 55

Having thus described our invention, what we claim as new and desire to secure by Letters Patent, is—

A grinding tool comprising a hollow conical holder, a metal mass within the holder, a grinding element having a frusto-conical base extending within the smaller end of the holder and embedded in the metal mass, said metal mass having a screw-threaded bore to receive an actuating shaft or spindle. 70

In testimony whereof we hereunto affix our signatures in the presence of two witnesses.

STANLEY VENGRIN.
JOHN M. JOHNSON.
